SWITCH STRUCTURE

Fredric E. Wood, Oak Park, Ill., assignor to Automatic Electric Laboratories, Inc., a corporation of Delaware

Application September 21, 1942, Serial No. 459,121

5 Claims. (Cl. 200—166)

The present invention relates to switch structure and more particularly to fixtures for securing operating elements to switch springs.

The principal object of the present invention is to provide an improved fixture for securing an insulating operating element to a metallic switch spring, which is of simple and rugged construction and which is economical to manufacture.

Another object of the invention is to provide an improved metallic fixture for supporting an insulating operating element, which fixture is adapted to be welded to a thin flexible switch spring in a simple manner without weakening, straining or otherwise injuring the switch spring.

The invention, both as to its organization and method of operation, together with further objects and advantages thereof, will best be understood by reference to the following specification taken in connection with the accompanying drawing, in which Figure 1 is a plan view of an electromagnetic relay incorporating switch structure embodying the present invention; Fig. 2 is a side elevational view of the relay shown in Fig. 1; Fig. 3 is a fragmentary side elevational view, partly in section, of the relay; and Fig. 4 is an enlarged sectional view, taken along the line 4—4 in Fig. 1, of a portion of the switch structure incorporated in the relay.

Referring now more particularly to Figs. 1 to 4, inclusive, of the drawing, the electromagnetic relay there shown comprises a magnetic core 10 carrying a winding 11, a substantially L-shaped magnetic field element 12 secured to the core 10, and a movable magnetic armature 13 pivotally mounted on the outer end of the field element 12 and cooperating with the outer end of the core 10. More particularly, a nonmagnetic shim 12a formed of bronze or the like is carried on the upper surface of the field element 12 adjacent the outer end thereof, and a pivot pin 14 is rotatably mounted on the upper surface of the shim 12a by an arrangement comprising a clamping member 15, a washer 16 and a screw 17, the pivot pin 14 being arranged in a transverse slot 15a formed in the clamping member 15. The screw 17 extends through aligned holes provided in the washer 16, the clamping member 15 and the shim 12a, and the outer end thereof is received in an aligned tapped hole provided in the field element 12 adjacent the outer end thereof. Also a downwardly bent tab 16a is formed integrally with the washer 16 and extends through a recess 15b formed in the clamping member 15 into aligned openings provided in the shim 12a and the field element 12, thereby positively to pre-

vent relative motion between the clamping member 15 and the field element 12. Preferably, the pivot pin 14, the clamping member 15, the washer 16 and the screw 17 are all formed of non-magnetic material in order to prevent these elements from interfering with the magnetic flux path between the field element 12 and the armature 13.

Further the armature 13 carries a pair of spaced-apart and inwardly directed arms 18 disposed on the opposite sides of the field element 12 and provided with aligned holes therein which receive the opposite outer ends of the pivot pin 14, the opposite outer ends of the pivot pin 14 being flanged over in order rigidly to secure the pivot pin 14 to the arms 18 and consequently to the armature 13. Also the arms 18 are provided with inturned operating projections 18a which overlie the upper surface of the shim 12a and cooperate with switch structure 19 carried by the field element 12. More particularly, the switch structure 19 comprises a plurality of individual flexible metallic switch or contact springs 20, 21, etc., arranged in two stacks and respectively secured to the field element 12 by two pairs of screws 22 and 23. More specifically, the base ends of the springs 20, 21, etc., in each stack are spaced apart and insulated from each other by a plurality of interposed insulating sheets 24 which are retained in clamped position between a clamping plate 25 and the field element 12 by the two pairs of screws 22 and 23. For example, the pair of screws 22 extends through two sets of aligned holes formed in the clamping plate 25, the insulating sheets 24 and the base ends of the contact springs 20, 21, etc.

Preferably, in each stack, the two adjacent contact springs constituting a cooperating pair, such, for example, as the individual contact springs 20 and 21, are constructed and arranged in the manner disclosed in U. S. Patent No. 2,272,496, Fredric E. Wood, granted February 10, 1942. Accordingly, the contact spring 20 has a substantially Y configuration, the outer free end thereof being split to provide two diverging arms; while the contact spring 21 has a closed ovate-lanceolate slot formed therein near its free end in order to provide diverging and converging arms, the converging arms being connected together at the extreme free end of the switch spring by a curved operating portion 21a. Also the two diverging arms of the switch spring 20 carry two metallic contacts which are arranged in cooperating relationship with two metallic contacts carried by the two diverging arms carried by the contact spring 21, the two pairs of cooperating

contacts being arranged in crossing relationship as illustrated.

Further a substantially cup-shaped metallic fixture 30 is provided which comprises a flat bottom wall 31 and a substantially cylindrical side wall 32 which converges slightly away from the bottom wall, the bottom wall 31 of the fixture 30 being securely fastened to the adjacent lower surface of the curved operating portion 21a of the contact spring 21. Preferably, the bottom wall 31 of the fixture 30 is welded or secured by fused metal to the adjacent lower surface of the curved operating portion 21a of the contact spring 21. This construction is very advantageous in view of the fact that the contact spring 21 is formed of thin flat metallic spring stock; and the fixture 30 is formed by a suitable die operation from thin flat metallic stock. Hence the fixture 30 may be readily welded to the contact spring 21 without weakening the structure of the contact spring 21, which would occur in the event the fixture 30 were screwed, riveted or similarly fastened to the contact spring 21. Furthermore, the amount of heat which is generated in the contact spring 21 is not excessive, thereby preventing resultant strains therein which would occur in the event the fixture 30 were formed of relatively heavy stock.

Finally a substantially cylindrical insulating operating element or bushing 33 is arranged within the fixture 30 and frictionally secured in place by interlocking with the tapered side wall 32 thereof. Preferably, one end of the bushing 33 is provided with a frusto-conical section, which is inserted into the cup-shaped fixture 30, and then the side wall 32 of the fixture 30 is spun or pressed down into firm engagement with the conical side wall of the received section of the bushing 33. The bushing 33 cooperates directly either with the operating portion of an adjacent one of the contact springs or directly with the inturned operating projection 18a carried by one of the arms 18 of the armature 13. Preferably, the bushing 33 comprises a length which has been cut from a rod which has been especially prepared. More particularly, a rod is produced by winding into tight spiral form a sheet of paper, fabric or the like which has been impregnated with a phenolic or like resin, and then curing under heat and pressure. A bushing comprising a length of a rod of the construction described above is very advantageous in view of the fact that it does not have any plane of cleavage. Finally the lower end of the bushing 33 which engages the operating portion 21a of the adjacent contact spring or the inturned operating projection 18a carried by the arm 18 of the armature 13 is suitably rounded in order to insure smooth sliding action.

Considering now the operation of the relay, when the winding 11 is deenergized the contact spring 21 urges the bushing 33 carried thereby into engagement with the operating portion of the adjacent contact spring; while the bushing carried by the last-mentioned contact spring engages the inturned operating projection 18a carried by the arm 18 of the armature 13, whereby the armature 13 and the pivot pin 14 secured thereto are rotated in the counterclockwise direction, in an obvious manner. More particularly, the pivot pin 14 rotates in the transverse slot 15a formed in the clamping member 15, the adjacent upper surface of the shim 12a serving also as a bearing therefor. Also, at this time, the various metallic contacts carried by the contact springs 20, 21, etc., are moved into normal cir-

cuit positions. When the winding 11 of the relay is energized the armature 13 is attracted toward the core 10 by the magnetic flux produced in the field structure, whereby the armature 13 and the pivot pin 14 secured thereto are rotated in the clockwise direction, in an obvious manner. This rotation of the armature in the clockwise direction causes the inturned operating projection 18a carried by the arm 18 to act upon the bushing carried by the associated contact spring and through the operating portion of the contact spring mentioned upon the bushing 33 and consequently upon the contact spring 21. Accordingly, the contact springs mentioned are flexed, whereby the various metallic contacts carried by the contact springs 20, 21, etc., are moved into operated circuit positions.

It is noted that the end of the shim 12a underlying the projections 18a carried by the arms 18 of the armature 13 prevents the projections mentioned from sticking to the adjacent surface of the field element 12 due to leakage magnetic flux therebetween. The construction of the armature and the means for mounting it on the field member are claimed in a copending divisional application Serial No. 573,676, filed January 20, 1945.

While one embodiment of the invention has been disclosed, it will be understood that various modifications may be made therein, and it is intended to cover in the appended claims all such modifications as fall within the true spirit and scope of the invention.

What is claimed is:

1. Switch structure comprising a metallic switch spring, a metallic fixture secured by fused metal to said switch spring, and an insulating element frictionally secured to said fixture, said element being adapted to be engaged by a cooperating movable operating member in order to control flexing of said switch spring.

2. Switch structure comprising a metallic switch spring, a metallic cup-shaped fixture having a bottom wall secured by fused metal to said switch spring and an outwardly projecting substantially cylindrical side wall which converges away from said bottom wall, and a substantially cylindrical insulating bushing arranged within said fixture and frictionally secured in place by interlocking engagement with the side wall thereof, an end of said bushing projecting outwardly from said fixture and being adapted to be engaged by a cooperating movable operating member in order to control flexing of said switch spring.

3. Switch structure comprising a thin flexible metallic contact spring having a free end and a stationary base end, a thin metallic cup-shaped fixture having a bottom wall secured to said contact spring adjacent the extreme free end thereof by fused metal and having an annular side wall provided with a part of reduced diameter spaced from said bottom wall, and an insulating element arranged within said fixture and frictionally secured in place by engagement with said part of reduced diameter, a portion of said element projecting outwardly from said fixture and being adapted to be engaged by a cooperating movable operating member in order to control flexing of said switch spring.

4. In a switching device comprising a thin flat flexible spring having a movable portion, a metallic cup-shaped fixture having a bottom wall secured to said movable portion of said spring and having an annular side wall projecting therefrom, and a substantially cylindrical non-metal-

lic bushing having a frusto-conical base portion seated within said cup-shaped fixture, said side wall being spun inwardly into engagement with said frusto-conical base portion to secure said bushing in place, an end of said bushing projecting from said fixture for engagement by a cooperating movable operating member for the purpose of flexing said spring.

5. In a switching device comprising a thin flat flexible spring having a movable portion, a metallic cup-shaped fixture having a bottom wall secured to said movable portion of said spring and having an annular side wall projecting therefrom, and a substantially cylindrical non-metallic

bushing having a frusto-conical base portion seated within said cup-shaped fixture, said side wall being spun inwardly into engagement with said frusto-conical base portion to secure said bushing in place, an end of said bushing projecting from said fixture for engagement by a cooperating movable operating member for the purpose of flexing said spring, said end of said spring having a curved end surface for engagement by said operating member to permit tilting of the movable portion of said spring in the event that one part of said spring meets opposition to movement before another part does.
